ELECTRIC SWITCH

Raymond N. Rowe, Plainville, Conn., assignor to
The Trumbull Electric Manufacturing Company, Plainville, Conn., a corporation of Connecticut

Application December 6, 1945, Serial No. 633,147

9 Claims. (Cl. 200—50)

1

My invention relates particularly to enclosed switches capable of connecting a load to either one of two sources of current or capable of connecting a source to either one of two loads.

One object is to provide such a switch with a quick make and break mechanism.

Another object is to ensure complete disconnection from one source before connection to the other.

Another object is to mount the contacts in the box body and the snap action mechanism on the cover so that each is exposed for independent inspection.

Another object is to prevent accidental actuation of the switch when the cover is open.

Another object is to provide mechanism in a switch of this character in which the make and break action is positive even in the event of spring failure.

Fig. 1 is a front view of a switch embodying one form of my invention, part of the cover being broken away so as to disclose the interior and the parts being shown in the open circuit position.

Fig. 2 is a fragmentary sectional view of the actuating handle on the plane of the line 2—2 of Fig. 1.

Fig. 3 is a vertical sectional view of the entire switch construction on the plane of the line 3—3 of Fig. 1.

Fig. 4 is a fragmentary vertical sectional view showing the interlock between the actuating handle and the movable switch member, the section being taken on the plane of the line 4—4 of Fig. 5.

Fig. 5 is a plan view of the parts shown in Fig. 4 and a section on the plane of line 5—5 of Fig. 3.

Fig. 6 is a drop perspective view of parts of the driving connection.

Fig. 7 is a view showing the driving and throwing mechanism in the open circuit or "off" position.

Fig. 8 is a similar view showing the throwing mechanism in a closed or "on" position.

Fig. 9 is a plan view showing part of the switch interior.

Fig. 10 is a diagram of the circuits of the switch of Fig. 9.

The body of the box 10 has a cover 11 hinged at 12 and provided with clamps 13 for the other edges. The switch 14 per se, may be of any suitable type having two sets of stationary contacts 15, 16 and a movable switch member 17 carried by a rotatable shaft 18. An arm 19 is secured to the outer end of shaft 18 and extends later-

2

ally therefrom. Its outer end is adapted to slide across the track 20 carried by the box. The parts are shown in the "off" position in Figs. 1, 3 and 5. A spring lever 21 is mounted on the arm 19 and under pressure of a spring 22 on the post 23. A pin 24 is carried by the spring lever 21 and when the cover is open projects down through the arm 19 into a hole in the stationary track 20 so as to prevent the arm and shaft from being accidentally turned. By pressing down on the inner end of the spring lever 21, it is tilted to the position of Fig. 3 so that the pin 24 is retracted from the track and the arm and shaft are free to be rotated. This tilting is done automatically by the post 25 carried by the cover when the cover is closed and may be effected manually when the cover is open.

The shaft 18 and its arm 19 are rotated by means of a disc 26 mounted on a central post 25. 20 This disc is supported at its periphery by a number of guides 27 and pressed downwardly by a spring 28 on post 25. The rim of disc 26 has a slot 29 with sloping sides adapted to receive the post 23 on the arm 19 when the cover is closed. 25 Power to rotate the disc is applied by the external handle 30 and two throwing springs 31 and 32, with lost motion connections, so that when the handle is moved to start the action and a spring is compressed to the driving point the 30 disc is rotated out of control of the operator to the "on" or "off" position as the case may be.

The details of the handle mounting shown herein are disclosed and claimed in my application Serial Number 619,999 filed October 3, 1945.

35 For the purpose of this application, it is sufficient to point out that the handle has a hub 33 rotatably supported in a bearing member 34 carried by the cover.

An annular member or ring 35 is mounted for 40 limited rotation on this hub 33, for instance, the hub may have a disc with a cut-out 36 in one edge and the ring may have a projection 37 of less circumferential extent projecting into the cut-out 36.

45 The springs 31, 32 are mounted on rods 31' and 32' which have fixed abutments 38 and 39 and forked connections with pins 40 and 41 on the ring 35 when the parts are in the "off" position. Each rod also maintains engagement with its pin while 50 the parts are being moved to the closed circuit position in each direction during which time the other rod is disconnected from its pin and presses against pin 42 on ring 35. Pins 42' limit outward movement of the springs.

55 Ring 35 carries a roller 43 which operates in a

butterfly shaped opening 44 in the disc 26. In the "off" position, the roller stands in the curved central part of this opening 41' as shown in Fig. 7. The ring 35 has two lugs 45 which extend toward the disc in position to coact with its projections 46 to hold the disc in the "off" position.

Rotation of the handle 30 rotates the hub and the annular member or ring and thus compresses one of the springs depending upon which direction the handle is turned. The opening 44 in the disc has a cam-like edge 47 against which the roller 43 presses when the handle is rotated toward either one of the "on" positions. This starts to rotate the disc slowly at first under the operator's control. As soon as the pin 40 or 41 as the case may be is rotated past the center line the spring which has been compressed by this action suddenly throws the ring and its roller in its direction out of the operator's control until the roller reaches the outer end of the opening 44. By this movement, the circuit is closed.

To open the circuit, the handle is turned in the opposite direction during which time the roller 35 engages the edge 48 of the opening in the disc and turns the disc backward while the spring is being compressed. This will result in a quick break as soon as the compressed spring passes the line of centers.

The switch per se in the form shown has a stack of insulating discs 50 with the contacts between them. This is claimed in my application Ser. No. 652,586, filed March 7, 1946.

Fig. 9 is a plan view showing one form of mechanism suitable for use with this invention.

In the diagram of Fig. 10, the stationary contacts 16 are shown connected to the ship's service supply lines S+S- and to the load lines L+L-. The stationary contacts 15 are similarly connected to the emergency supply lines E+E- and to the load lines L+L-. The movable contacts 17', 17 and 17' rotate together as a part of the switch member 17 and serve to connect the ship's service supply to the load when the switch member 17 is rotated counterclockwise and to connect the emergency supply to the load when the switch member 17 is rotated clockwise. It will be understood that although the particular switch shown was designed for ship's use that the invention is adapted for use wherever it is desired to have two independent sources of supply which can be readily and safely applied to a load of any kind. Certain principles of this invention are adapted for embodiment in switches having more than two sources of supply as in my application Ser. No. 652,586.

By reason of the direct connection between the handle and the throwing disc the switch can be actuated even if the throwing springs should fail.

Various circuit arrangements are possible merely by varying the external circuit connections to agree with whatever type of system the switch is connected to, i. e. two or three wire systems.

I claim:

1. Throwing mechanism for a transfer switch including a disc having an eccentric opening with oppositely extending bays, a central shaft for said disc, an oscillatable ring, two oppositely compressible throwing springs operatively connected to said ring and a roller carried by said ring and coacting with the edges of the opening in said disc to rotate said disc partially about its shaft.

2. Throwing mechanism for a switch including a disc having an eccentric opening with oppositely extending bays, a central shaft for said disc, an oscillatable ring, two oppositely compressible

throwing springs operatively connected to said ring, said disc having stops coacting with said ring to hold back said disc until one of the springs is fully compressed and a roller carried by said ring and coacting with the edges of the opening in said disc to rotate the same upon movement of said ring.

3. Switching mechanism including a support, a disc rotatably carried thereby, a rotatable actuating handle carried by said support, an oscillatable member, two opposed throwing springs operatively connected thereto, a lost-motion connection between said handle and said oscillatable member, a lost-motion connection between said oscillatable member and said disc and means for connecting said disc to a movable switch member.

4. Switching mechanism including a box containing the switch contacts, a cover therefor, a disc rotatably carried by said cover, a rotatable actuating handle carried by said cover, an oscillatable member, two opposed throwing springs connected thereto, a lost-motion connection between said handle and said oscillatable member, a lost-motion connection between said oscillatable member and said disc and means for connecting said disc to a movable switch member.

5. The combination of a switch in a box having a cover, said switch having a rotatable member, an arm connected to said member and extending laterally therefrom, a stationary track in the box, a lever mounted to tilt on said arm and having a pin adapted to interlock with said track, means carried by the cover for engaging said lever to retract said pin and release the arm when the cover is closed and switch actuating means carried by the cover having means to interlock with said arm for rotating the rotatable switch member when the cover is closed.

6. The combination of a switch in a box having a cover, said switch having a rotatable member, an arm connected to said member and extending laterally therefrom, a lever mounted to tilt on said arm and lock said lever and arm, means carried by the cover for engaging said lever to retract the same and release the arm when the cover is closed and switch actuating means carried by the cover having means to interlock with said arm for rotating the rotatable switch member when the cover is closed.

7. Switching mechanism comprising a support, an actuating disc pivoted thereon to be turned a partial turn on its axis in both directions, an annular member eccentric to said disc and having two pins, a handle having a lost motion connection with said annular member, two oppositely arranged spring pressed throwing rods engaging said pins when the parts are in the "off" position, said disc having an opening with a cam-edge and two oppositely inclined edges, said annular member having a roller extending into said opening, said roller coacting with the cam edge for rotating said disc to either "on" position and coacting with the inclined edges for rotating said disc back to an "off" position.

8. Switching mechanism comprising a support, an actuating disc pivoted thereon to be turned a partial turn on its axis in both directions to close a circuit, an annular member eccentric with respect to said disc, said annular member and said disc having coacting projections for preventing accidental rotation of said disc from the "off" position, a handle having a lost motion connection with said annular member, two oppositely arranged spring pressed throwing rods connected to said disc when the parts are in the "off" po-

sition, said disc having a cam edge and two oppositely inclined edges, said annular member having a roller coacting with the cam edge for rotating said disc to either "on" position and coacting with the inclined edges for rotating said disc back to an "off" position.

9. The combination of a switch in a box having a cover, said switch having a rotatable shaft for actuating movable contacts of the switch, an arm connected to said shaft and extending laterally therefrom to move in a plane substantially parallel to the plane of the cover, a stationary track secured to the box and extending close to the path of movement of said arm, a lever mounted to tilt on said arm and having a formation to interlock the arm with said track, means carried by the cover for engaging said lever to retract

said formation and release the arm for movement when the cover is closed, and switch actuating means carried by the cover and having means to interlock with said arm for rotating the rotatable shaft to actuate the movable contacts of the switch when the cover is closed.
